UNITED STATES PATENT OFFICE.

ARTHUR CROCKETT, OF KANSAS CITY, MISSOURI.

TRAP-GUN.

1,348,543.

Specification of Letters Patent. Patented Aug. 3, 1920.

Application filed June 3, 1919. Serial No. 301,508.

To all whom it may concern:

Be it known that I, ARTHUR CROCKETT, a citizen of the United States, residing at Kansas City, in the county of Jackson and 5 State of Missouri, have invented certain new and useful Improvements in Trap-Guns, of which the following is a specification.

The present invention relates to improvements in trap-guns designed primarily as 10 a means for destroying predatory and other animals by the self-destruction method.

An object in view is to provide a device 15 of this character which may readily be set in or on the ground near where the animal or animals frequent, a ground engaging support being provided for this purpose, a novel feature of which lies in the fact that it constitutes the retracting means for the 20 firing pin of the gun mechanism.

A further object in mind is the provision 25 of a bait holding means so arranged as to operate the trigger of the gun incident to the attempt on the part of the animal to remove the bait therefrom.

To this end the invention consists in the construction, combination and arrangement 30 of parts all as hereinafter more fully described, claimed and illustrated in the accompanying drawing, wherein:

Figure 1 is a side elevation of the device in set position, showing the preferred manner of arranging the gun;

Fig. 2 is a bottom plan view;

Fig. 3 is a longitudinal sectional view, showing the firing mechanism cocked and the dotted line position assumed by the ground engaging member in performing the cocking operation; and

Figs. 4 and 5 are sectional views on the lines 4-4 and 5-5, of Fig. 3, respectively.

Throughout the following detail description, and on the several figures of the drawing, similar parts are referred to by like 45 reference characters.

In the construction of the gun I provide a breech or body portion 1 having a longitudinal bore in which is disposed the firing mechanism hereinafter to be described. At 50 one end the barrel 2 is screwed into said breech against the cartridge seat 3 provided with a central opening through which the firing point projects to contact with the car-

tridge held in place by the barrel against the part 3 aforesaid.

Within the bore of the breech is mounted 55 the firing pin 4 surrounded by the impelling spring 5 which is adapted to actuate the hammer-block 6 through which the pin extends. The block 6 it will be obvious acts 60 as a guide for one end of the pin, while the retainer block 7 at the other end of the bore provides a further guide, the latter block being secured in place by the set-screw 8. The firing mechanism may be displaced 65 from the breech by the removal of this screw, which in turn permits the withdrawal of the other parts within the bore. The lower end of the breech receives the supporting stob or spike 9 which carries a locking 70 screw 10 engaging in a cut-out portion 11 in the lower end of the firing pin which projects into the stob, this cut-out portion being so formed as to permit of relative movement between the pin and the stob.

The locking screw not only performs the function of connecting the pin to the stob 75 as aforesaid, but furthermore locks the breech and stob together in one position of the latter, an L-shaped slot 12 being provided in the lower end of the breech for this purpose.

Upon one side of the breech is pivotally mounted the trigger 13, one end 80 of which projects into the breech to engage with the hammer-block 6 when the latter is retracted for cocking the gun. The opposite end of the trigger is engaged by a spring 85 14 which tends to hold the trigger in its engaging position. The trigger has connected thereto the bait holding means 15 which consists of a piece of strong or stiff wire, preferably formed with a loop surrounding the barrel, as indicated at 16, at an intermediate point, thus providing a guide, while terminating in the hook 17 arranged 90 proximate to the end of the barrel, but out of the plane of the bore. At the end of the barrel is arranged a projection 19 which forms a stop against which the loop 16 takes up when the bait is snatched by the animal. 100

With the foregoing in mind, the use and operation of the device will now be explained. The gun is loaded with a cartridge by removing or unscrewing the barrel 2 and slipping the cartridge into the end thereof, 105 replacing the barrel until the cartridge is

clamped against the partition or seat 3. Having placed the bait upon the hook 17, the stob or support 9 is now disengaged or unlocked from the breech by giving the same 5 a slight turn to move the locking screw 10 from the slot 12 and then pulling outwardly. This action retracts the firing pin 4 which is provided with a collar or enlarged portion 18, engageable with the hammer-block 6, the latter being drawn back against the 10 tension of the spring 5 until the trigger 13 engages and locks the same in cocked position. The stob 9 is now pushed back into the breech to bring the firing point of the 15 pin into its proper operative relation to the cartridge, whereupon the stob is again turned in the breech slot so as to lock the pin in this position. The loaded gun is now ready to be placed in the desired position, most accessible to the animal to be killed, 20 this being accomplished by sticking the stob or spike into the ground, preferably at a slight angle, as shown in Fig. 1. When the animal attempts to remove the bait, the wire 25 15 is pulled, actuating the trigger and releasing the hammer-block 6 which strikes the head 18 of the pin, firing the cartridge. Owing to the position of the animal's head in taking hold of the bait, it will receive 30 the missile from the gun.

From the foregoing, it will be seen that the device is extremely simple but effective in operation.

Having thus described my invention, what 35 I claim as new is:—

1. A trap gun of the class described comprising a breech, firing mechanism therein including a firing pin and trigger operating bait sustaining means, and a ground support for said gun connected with the mechanism for holding the bait means in accessible position and movable to cock the mechanism, said pin being free to move to the support after cocking of said mechanism 40 and without movement of said support in firing the gun.

2. A trap-gun of the class described comprising a breech, firing mechanism therein including trigger operating bait sustaining means, and movable ground engaging means adapted to hold the gun in operative position, said means being connected with the firing mechanism and operable to cock the gun, but stationary during firing thereof.

50 3. A trap-gun of the class described comprising a breech, firing mechanism therein including a trigger and firing pin, and a support for said gun operatively connected to the pin and operable to retract the same 55 for cocking the gun, said support being held relatively stationary with respect to the pin in firing the gun.

4. A trap-gun of the class described comprising a breech, a firing pin therein, bait holding means for effecting actuation of the

pin and a movable support for said gun operatively connected to the pin and movable to cock the gun, said support being engageable with the breech to lock the pin in firing position when the gun is cocked but 70 relatively movable with respect to the support.

5. A trap-gun of the class described comprising a breech, firing mechanism mounted therein comprising a firing pin, a hammer device co-operative with the pin and movable relative thereto, bait holding means for releasing said hammer device when the gun is cocked, and supporting means for the gun 75 operable to cock the gun through the firing pin.

6. A trap-gun of the class described comprising a breech, firing mechanism mounted therein, including a trigger adapted to be operated by an animal in seizing bait a 85 firing pin, a hammer-block mounted upon the pin and movable relative thereto, and supporting means for the gun connected with the pin and operable to retract the same and the hammer-block therewith to cocked position, said supporting means thereafter remaining stationary in the firing of the gun. 90

7. A trap-gun of the class described comprising a breech, firing mechanism mounted therein comprising a firing pin, a hammer block co-operative with the pin and movable relative thereto, a trigger engageable with said block to hold the same retracted, bait holding means connected to said trigger, means engageable with the pin for retracting 100 the hammer block to cocked position, said pin being movable into operative firing position by the means aforesaid after the gun is cocked, and means for interlocking the pin engaging means aforesaid with the breech to lock the pin in the said firing position.

8. A trap-gun of the class described comprising a breech, a firing pin mounted therein, trigger means including a bait holder and a ground engaging spike arranged at one end of the breech for supporting the gun in operative position, said spike being connected to the pin for shifting the same to and from firing position. 110

9. A trap-gun of the class described comprising a breech, having a longitudinal bore, a firing pin mounted therein, a hammer-block in the bore engageable with the pin, a spring adapted to actuate the hammer-block, a stob connected to one end of the pin and operable to retract the same and the block therewith, a trigger engageable with said block, and a bait holder connected to the trigger and extending to a position 120 adjacent to the mouth of the bore.

10. A trap gun of the class described comprising a breech, a barrel connected thereto at one end, a trigger pivotally mounted on the breech, a bait holding device comprising 125

a wire engageable with the trigger at one end and having a loop intermediate its length surrounding the barrel to provide a sliding connection therewith, firing mechanism in the breech including a hammer block and retainer block removably mounted therein and a firing pin guided in its move-

ments by the latter block, and a spike-like supporting member connected to the breech and disengageable therefrom to permit of 10 operation of the firing pin, by the supporting member.

In testimony whereof I affix my signature.
ARTHUR CROCKETT.
